REMOVABLE DRUM TYPE TOBACCO CUTTING MACHINE WITH FIXED GRINDING MEANS

Max Pollmann, Hamburg-Bergedorf, Germany, assignor to Kurt Korber & Co. K. G., Hamburg-Bergedorf, Germany

Application February 5, 1954, Serial No. 408,525

Claims priority, application Germany February 16, 1953

3 Claims. (Cl. 146—119)

The present invention relates to a tobacco cutting machine and is particularly concerned with a drum cutter in which the tobacco leaves are fed to a mouthpiece by conveyor means and having a cutter drum rotatable transversely in front of the mouthpiece and removable therefrom and a grinding device for grinding the cutters fitted to the periphery of the cutter drum.

Drum tobacco cutters are known in which the cutter drum and the grinding device are supported on a common mounting. In order to begin the cutting operation or be able to inspect the mouthpiece the mounting with the cutter drum supported thereon is removed from the mouthpiece either about an axis which is located vertically at one side of the machine frame or about an axis which lies horizontally below the mouthpiece. On turning away or removing the mounting with the cutter drum and the grinding device comparatively large masses consequently must be moved by the attendant. To this disadvantage there is also added a further disadvantage that the vibration occurring during rotation of the cutter drum and of the grinding wheels and during the reciprocatory movement thereof along the cutter edges affect one another mutually and in some cases are additive whereby the cutting operation and the grinding of the cutters become inexact.

These disadvantages are eliminated according to the invention by the fact that the grinding device is associated with the machine frame while the cutter drum is supported in a frame separate therefrom and can be rocked away from the mouthpiece or otherwise removed and can be brought out of engagement with the grinding device. By this construction the result is obtained that the movable assembly can be made lighter since it only has to carry the cutter drum. Moreover the overall length of the machine is considerably shortened if the grinding device is, as is preferred, arranged above the cutter drum. Finally a better grinding action is obtained since the grinding device remains associated with the major mass of the machine frame.

Tobacco drum cutters are, of course, known in which only the cutter drum is moved away from the mouthpiece toward the grinding device. These constructions have, however, the disadvantage that they can either only be operated for cutting or for grinding while according to the invention grinding and cutting can be simultaneously performed.

One constructional form of the invention is shown by way of example on the accompanying drawings wherein:

Fig. 1 is a side view of a tobacco drum cutter with the cutter drum mounting in the working position.

Fig. 2 is a view from above of the tobacco cutter but with the cutter drum mounting turned out of the operative position.

Fig. 3 is an enlarged partial section through the tobacco cutter according to Fig. 1, and

Fig. 4 is a view from above of the grinding device on a larger scale.

As shown in Fig. 3 the tobacco 1 is pressed in known

2

manner, for example continuously, through a mouthpiece 2, by means of conveyor belts 3 and 4 converging towards the mouthpiece and travelling in the direction of the arrows (see also Fig. 1) and which are driven by a

5 suitable driving device for example electric motor 5 through a belt 5a and a reduction gear train 5b likewise in known manner. A cutter drum 7 rotates in front of the mouthpiece 2 in the direction of the arrow 7' having for example five cutters 6 on its periphery and by which 10 the tobacco leaving the mouthpiece is cut. The cutters 6 are adjusted during rotation of the drum 7 by means of the known devices 6a and are sharpened by the grinding wheels 29 and 30, in similar manner as disclosed in Arthur Ritscher's United States patent specification 15 2,751,949, issued June 26, 1956. The cutter drum 7 is driven, for example by a driving motor 9 connected by its flange 9a to a frame 8 (see also Fig. 2).

In order to provide ready access to the mouthpiece 2

20 the frame 8 with the cutter drum 7, driving motor 9 and the tobacco delivery funnel 10 (see Fig. 3) is pivotally mounted on the stationary machine frame 15 (see Figures 1 and 2) by means of hinges 12, 12'. During cutting the frame 8 is locked by a device 13, to the stationary machine frame 15.

25 The grinding device described in further detail below is arranged above the cutter drum 7 (see Fig. 3) which device is mounted to the top of the machine frame 15 of the tobacco cutter.

Two bearing brackets 16 and 17 secured in suitable manner to the top portion of the machine frame 15 carry two guide bars 18, 18' arranged one over the other and preferably parallel to the cutter drum axis. A longitudinally reciprocable slider body 21 is supported on the guide bars 18, 18' (see Figs. 3 and 4), the rear side of 35 which carries a pin 31 on which a connecting rod 32 is attached which is driven by a crank 33 for example from a driving motor 34 supported on the machine frame 15.

On the other side of the slider body 21 is a plate 22 of dovetail form which can slide up and down on the horizontally movable slider member 21 by means of a ratchet wheel 23 fixed to a vertical screw spindle 24. The ratchet wheel 23 is operated by a pawl 25 which receives its movement from a lever 26 which travels by its other end during the reciprocation of the slider body 21 on the stationary cam tracks 27 and 27'. An electric motor 28, with for example a grinding wheel 29, 30 on each end of the shaft, is mounted on the plate 22. This movement at right angles to the reciprocatory movement and coupled thereto in the same manner as in machine tools has the effect that as the grinding wheels become smaller the motor with the two wheels can be fed automatically to the cutters. The grinding is here effected in such a way that each grinding wheel overlaps in its movement the centre of the cutter length by about 5 mm.

55 The trueing of the grinding wheels is effected in known manner by two adjustable diamond trueing devices 35, 35' which are arranged below the grinding wheels but outside the path of the cutters and preferably at a suitable point of the frame 8 in a suitable support device. The grinding dust, produced by grinding the cutters is collected in a container 36 from which it can be drawn off in some cases by means of lateral apertures 37, 37' connected to a suction device of known kind.

60 It is of no importance for the basic construction of the invention whether the cutter drum is arranged squarely or inclined to the mouthpiece since the inclination of the guide bars 18, 18' can be arranged to correspond to that of the cutter drum.

65 70 What I claim is:

1. A rotary tobacco cutter, comprising a machine frame having an enlarged elongated discharge passage forming a mouthpiece for discharging tobacco, means

mounted in said machine frame for feeding tobacco to said mouthpiece, a cutter frame hingedly connected to said machine frame on one side of said mouthpiece to swing horizontally to and from said mouthpiece, a grinding wheel mounted on said machine frame to move horizontally above said cutter frame parallel to said mouthpiece, a rotary cutter supported by said cutter frame having a plurality of circumferentially spaced knives to co-act with said mouthpiece and cut the tobacco into comminuted particles, means on said cutter frame for latching the swinging end of said cutter frame in position to hold the same to the machine frame in position below said grinding wheel and means supported on the rotary cutter frame for dressing the grinding wheel as the same is moved horizontally to traverse the cutting blades.

2. A rotary tobacco cutter, comprising a machine frame having an elongated discharge opening forming a mouthpiece, endless conveyor means mounted in said machine frame for feeding tobacco to said mouthpiece, a cutter frame hingedly connected to said machine frame on one side of said mouthpiece to swing horizontally toward and away from said mouthpiece, cutter blades carried by said cutter frame and arranged to rotate in spaced relation from said mouthpiece, a grinding wheel mounted on said machine frame to move horizontally above said cutter frame parallel with said mouthpiece, means on said cutter frame for latching the swinging end of said cutter frame in a locked position on the machine frame to position said cutter blades beneath said grinding wheel, and grinding wheel dressing tools mounted on the rotary cutter frame adapted to dress the grinding wheel peripheral surfaces when the grinding wheel is moved horizontally to traverse said cutter blades and an electric motor mounted on said rotary cutter frame having a power shaft drivingly connected to said cutter blades to rotate the same in slightly spaced relation from the edge of said mouthpiece, said cutter frame being normally positioned beneath said grinding wheel and being adapted to be

moved away from said mouthpiece and machine frame for repairs and cleaning purposes.

3. In a tobacco cutting machine, a frame having an elongated horizontal discharge opening forming a mouthpiece, means mounted in said frame for feeding tobacco to said mouthpiece, a rotary cutter drum frame hinged to said first named frame on one side of said mouthpiece to swing toward and away from said mouthpiece, a rotary cutter drum mounted in said cutter drum frame, motor means carried by said cutter drum frame drivingly connected to said cutter drum, latching means on the free swinging end of said rotary cutter drum frame for locking said frame to said first named frame so that the knives of the cutter drum will cooperate with said mouthpiece to cut tobacco fed therethrough, horizontal guideways on said first named frame arranged parallel to said mouthpiece, a horizontally movable carriage movable along said guideways a grinder having a rotary grinding wheel on said carriage whereby upon movement of said carriage the grinding wheel of said grinder will sharpen the knives of said rotary cutter when the rotary cutter frame is in its locked position, means supported by said first mentioned frame for reciprocating said carriage to cause the grinder to traverse the knives of said rotary cutter, and means attached to said carriage for feeding said grinder downward toward the rotary cutter drum, said motor for driving the rotary cutter drum being mounted on the cutter drum frame and adapted to rock therewith when said cutter drum frame is moved toward and away from said mouthpiece.
